ELECTRIC SWITCH

John P. Ruth, New York, N. Y., assignor to General Electric Vapor Lamp Company, Hoboken, N. J., a corporation of New Jersey

Application November 13, 1935, Serial No. 49,625

4 Claims. (Cl. 200—87)

The present invention relates to electric circuit makers and breakers, and particularly to those operating in a vacuum or other conditioned atmosphere.

5 A particular object of the invention is to provide a magnetically operated vacuum switch which will be reliable and certain in operation. Another object of the invention is to provide a switch of this type which will be simple and inexpensive, and which will have a long useful life. 10 Another object of the invention is to provide a switch which is easily assembled with a predetermined relation between the operating parts. Still other objects and advantages of the invention will 15 appear from the following detailed specification or from an inspection of the accompanying drawing.

The invention consists in the new and novel device hereinafter set forth and claimed.

20 Switches in which the circuit is made and broken between solid contacts in a vacuum, particularly in response to a magnetic field, are of especial value in many electrical circuits. For example, such a switch has been found to be unusually effective as a so-called shifter to provide 25 the surge in starting the well known Cooper-Hewitt mercury vapor arc lamps. The switch disclosed by Warren R. Walker in his Patent 1,984,505, granted December 18, 1934, has been 30 used very successfully for this purpose, and has already gone into extensive use. This type of switch, however, requires considerable glass working skill in the assembly thereof.

I have now discovered that the manufacture of 35 this type of switch can be greatly simplified and the cost thereof appreciably reduced by a novel construction of my invention. At the same time this novel structure inherently results in the certain and dependable operation of the switch and 40 eliminates the possibility of failure thereof due to faulty technique in the manufacture of the switch.

According to my invention the armature and 45 the contacts of my novel switch are assembled in a predetermined relation such that their alignment and spacing is rendered independent of the glass working operation by which they are sealed into the enclosing envelope. Furthermore the freedom of movement of the armature is so controlled that the diameter of the enclosing envelope has no effect thereon, and this armature, together with its associated circuit closing member, is positively precluded from touching any 50 part of the device whose dimensions are not under a close and positive control. Thus the pos-

sibility of the circuit closing member being jammed or stuck in the open circuit position is 5 positively precluded under all conditions. Likewise my novel structure results in the contact surfaces being far removed from all welds, whereby it is easy to obtain a clean, undistorted contact surface of low resistance. As a result of 10 these novel features my novel switch is readily assembled without the use of skilled labor and with the assurance that every switch will be perfect and dependable in operation throughout a 15 long useful life.

For the purpose of illustrating my invention I have shown a preferred embodiment thereof in 20 the accompanying drawing, in which

Fig. 1 is an elevational view, in part section of a switch which is especially designed for use as a shifter, and

Figs. 2 and 3 are cross-sectional views of the 25 switch of Fig. 1, taken on the lines 2—2 and 3—3, respectively.

As shown in this drawing my novel switch has a tubular sealed envelope 1 having an inlead 2 of tungsten or other suitable metal sealed axially into each end thereof through a reentrant seal 3. 30 At a point near said seals a strip of molybdenum 4 is welded to the upper side of each of the inleads 2, preferably with the aid of an interposed strip of nickel 5, with the free end of the molybdenum strip extending toward the inner end of said inlead and the free end of the nickel strip extending 35 toward the seal. A cylindrical insulator 6 of porcelain or the like is positioned on each of the inleads 2 with one end close to the seal 3. Each of said insulators has a substantially triangular opening 35 therein which closely fits the inlead 2 and the attached molybdenum strip 4, whereby rotation of said insulator on said inlead is precluded. The end of the molybdenum strips 4 are bent upwardly against said insulators to retain 40 them in position, and to serve as auxiliary contacts. Each insulator 6 likewise has a pair of recesses 8 therein at a point below the inleads 2 into which are fitted a pair of wires 9 of a suitable non-magnetic metal which positively space 45 and align the ends of the switch. A U-shaped member 10 of non-magnetic material is supported by the wires 9, with the vertical ends of said member extending past, but out of contact with, the inleads 2. In practice the wires 9 and 50 this member 10 are both made of iron alloyed with 18% nickel and 8% chromium, this being non-magnetic in the annealed state. A vertical slot 11 from which all burrs have been removed 55 is provided in each end of this member opposite

the ends of the inleads 2, and a tungsten wire 12 which serves to bridge the circuit between these inleads extends through said slots. At rest said wire lies upon said inleads, but the slots allow 5 vertical movement of said wire away therefrom to open the circuit. A tubular armature 13 of steel or the like is loosely mounted on the wire 12 between the legs of the U-shaped member 10 and serves to actuate the wire 12 to an open circuit 10 position when attracted by an external magnet suitably located above the envelope 1. The ends of this tubular armature are preferably slightly rounded, as by ball milling, in order to insure freedom of movement thereof. A getter pellet 14 15 containing magnesium or the like is welded to one of the nickel strips 5 at a point adjacent to a seal 3.

The manufacture of this switch is extremely simple and requires neither skilled glass working 20 nor any special selection of glass tubing for the envelope, due to the novel construction employed. Thus first of all the tungsten inleads 2 have a flare sealed thereto as at 3. The flat nickel and molybdenum strips 4 and 5 are then welded 25 thereto, and the getter pellet 14 attached to one of the nickel strips 5. An insulator 6 is then slid onto each inlead 2, and locked in a fixed position thereon by bending the end of the molybdenum strip 4 upwardly against said insulator. It will 30 be noted that the point of weld on each inlead is within the insulator 6, and is thus remote from the contact making position of said inlead, the latter being thus kept clean and undistorted during this assembly process. A pair of wires 9 are 35 then slipped through suitable slots in the U-shaped member 10 and welded in place. The wire 12 is then slipped into position through the slots 11 and the armature 13, the latter being thereby locked in position. The wires 9 are then slid into 40 position within the recesses 8 in the insulators 6 of the previously assembled parts, where they are held with sufficient friction to provide a readily handled unit in which all the parts are held in a predetermined relation and alignment. The 45 flares are then sealed into a suitable tubular envelope 1, after which the device is evacuated and sealed off in a conventional manner. In some cases, where a less abrupt opening of the circuit is desired, the device may of course be filled with 50 any suitable inert gas, such as hydrogen at any desired pressure.

In the operation of this switch the armature 13 is attracted upwardly by any suitable magnetic field, such as that produced by the electro- 55 magnet schematically represented by dotted lines in Fig. 1. Said armature thereupon strikes a hammer blow upon the wire 12, causing the latter to move upwardly away from the inleads 2 to open the circuit. In practice this hammer blow 60 is obtained through making the wire 12 of 45 mil tungsten where the bore of the armature 13 has a diameter of 80 mils, whereby said armature travels an appreciable distance before it engages said wire. This of course tends to separate any partially fused contacts. In addition this construction allows the wire 12 to rotate about any point of fusion, which is always limited to one end of said wire at any one time, and as a result of both 65 these factors it has been found that the circuit 70 through this novel switch is opened with certainty under all conditions. In its open circuit position the wire 12 is held against the top of the slots 11. Upon removal of the magnetic attraction the armature 13 drops, allowing the wire 12 75 to fall back into a circuit closing position under

the guidance of said slots 11 and the smooth upturned ends of the molybdenum strips 4. In this connection it may be noted that these strips 4 have sufficient area that the wire 12 can never pass over the edge thereof in any position permitted by the slots 11. The circuit is thereupon ordinarily closed by the wire 12 coming to rest on the inleads 2, although if the axis of the switch is at an angle to the horizontal one end of the wire 12 may rest against a molybdenum strip 4 10 while the other end rests upon the inlead 2. Either mode of operation is, of course, satisfactory, it being obvious that the circuit is closed with certainty in either case.

In addition to the decreased cost of manufacture of my novel switch, which largely arises from the fact that no skilled and tedious glass working operations are required, it has been found that the controlled movement of the armature 14 and wire 13 results in a uniform product 20 of high efficiency and dependability.

While I have described my invention by reference to a particular embodiment thereof it is to be understood that it is not limited thereto, but that various omissions, substitutions and changes, 25 within the scope of the appended claims, may be made therein without departing from the spirit of my invention.

I claim as my invention:—

1. An electric circuit maker and breaker comprising a sealed envelope, two fixed contacts sealed into said envelope, a relatively long bridging member extending between said contacts, said fixed contacts being spaced apart a distance slightly less than the length of said member whereby each end of said member engages one of said contacts, means comprising smooth metal strips connected to said contacts to prevent axial displacement of said member, means independent of said envelope and insulated from said contacts to prevent movement of said member beyond the edges of said strips, and a magnetizable body loosely connected to said bridging member.

2. An electric circuit maker and breaker comprising a sealed envelope, two fixed contacts within said envelope, means within said envelope to space said contacts a fixed distance apart, said means consisting at least in part of insulating material, a relatively long bridging member extending between said contacts with each end resting upon one of said contacts, means to prevent axial displacement of said member, means independent of said envelope to limit the movement of said member away from said contacts, and a magnetizable body loosely connected to said bridging member.

3. An electric circuit maker and breaker comprising a sealed envelope, two fixed contacts sealed into said envelope, a relatively long bridging member extending between said contacts, said fixed contacts being spaced apart a distance slightly less than the length of said member whereby each end of said member engages one of said contacts, means comprising smooth metal strips connected to said contacts to prevent axial displacement of said member, means within said envelope to rigidly space said strips and to prevent rotation thereof with respect to each other, said means consisting at least in part of insulating material, means independent of said envelope to prevent movement of said member beyond the edges of said strips and a magnetizable body loosely connected to said bridging member.

4. An electric circuit maker and breaker com-

prising a sealed envelope, two fixed contacts within said envelope, an insulator mounted upon each of said contacts and locked against rotation thereon, means within said envelope to separate said insulators by a fixed distance and to prevent the relative rotation thereof, a relatively long bridging member extending between said contacts with each end thereof resting upon one of said contacts, means comprising smooth

metal strips connected to said contacts to prevent axial displacement of said member, a slotted guide member mounted on said insulator separating means adjacent each contact to prevent movement of said member beyond the edges of said strips, and a magnetizable sleeve loosely mounted upon said bridging member between said guide means.

5

JOHN P. RUTH.
